UNITED STATES PATENT OFFICE.

AUGUST WAGNIERE, OF LOS ANGELES, CALIFORNIA, ASSIGNOR TO E. W. PECK AND T. R. OWEN, BOTH OF LOS ANGELES, CALIFORNIA.

PENCIL-VENDING MACHINE.

931,903.

Specification of Letters Patent. Patented Aug. 24, 1909.

Application filed July 27, 1908. Serial No. 445,680.

To all whom it may concern:

Be it known that I, AUGUST WAGNIERE, a citizen of the United States, residing at Los Angeles, in the county of Los Angeles and 5 State of California, have invented a new and useful Pencil-Vending Machine, of which the following is a specification.

This invention relates to pencil vending machines and has for its object to simplify 10 the construction of the same and thereby attain economy of manufacture.

Referring to the drawings:—Figure 1 is a vertical sectional view through the machine, part of the coin chute being broken away, 15 the parts being shown in normal position ready for the insertion of a coin. Fig. 2 is a section on line x^2-x^2 Fig. 1, a coin having been inserted and unlocked the apparatus ready for operation. Fig. 3 is a view similar 20 to Fig. 2, showing the position of the parts after the operating bar has been pushed in. Fig. 4 is a section on line $x-x^4$ Fig. 1, the locking device being shown in dotted lines tilted into unlocking position. Fig. 5 is a 25 perspective view, enlarged, of the operating bar. Fig. 6 is a perspective view of the locking device. Fig. 7 is a perspective view of the coin receptacle.

1 designates the base of the box with side 30 walls 2, a back wall 3 and a removable front wall 4.

5 is the top.

A shelf 6 is arranged above the bottom 1 and an ejecting space 7 is formed back of the 35 shelf 6 next the back wall 3, through which space the pencil is allowed to pass when the machine is operated. A pair of vertical ways 8 are secured to the back wall 3 and each is U-shaped in cross section, and the pencils 9 40 are arranged horizontally with their ends in the ways 8. A pair of inclined ways 10 are arranged on the bottom 1 underneath the shelf 6 and the pencil after passing through the space 7 rolls down the inclined ways 10 and out through a slot 11 formed in the lower 45 part of the front wall 4, the pencil after passing through the slot 11 dropping into a shallow groove 12. The grooves in the ways 8, as shown in Fig. 2, lie forward of the space 50 7 and the lowermost pencil normally rests on top of an ejector bar 13, the latter having off-set ends 14 which support the pencil and having a central rod 15 which is slidably mounted in a socket 16 secured to the shelf 55 6. A flat spring 17 bears against the end of

the rod 15 and acts to move the ejector bar rearwardly into its normal position as in Fig. 2. A lever 18 is pivoted at 19 to the shelf 6 and one end engages the rod 15 while the other end of the lever engages in a notch 20, 60 see Fig. 5, which is formed in the operating bar 21. The operating bar 21 is secured to a shoe 22 which slides in a plate 23, the latter being fastened flatly to the shelf 6. One side of the shoe 22 is provided with a series of 65 rectangular notches 24 and with two large concave notches 25 and 25^a at either end of the notches 24. A double acting pawl 26 is pivoted to the shelf 6 and has a coil spring 27 secured to one end of the pawl and to a screw 70 28 which tends to hold the pawl in a central position, but allows it to swing to either side from its central position.

When the operating bar 21 is in normal position, as in Fig. 2, the end of the pawl 26 75 lies in notch 25, the latter being deep enough to permit the pawl to lie in a central position. When the operating rod 21 is pushed inward the pawl clicks over the teeth 24 and prevents retraction of the operating rod un- 80 til the rod has been pushed the required distance, at which time the pawl 26 enters the notch 25^a, and the latter being sufficiently deep enables the pawl to swing in the other direction to permit the retraction of the operating rod, and during the retractive movement of the operating rod the pawl again 85 acts to prevent the rod from being pushed in until it has been fully retracted and the pawl again engages in notch 25. The ob- 90 ject of this pawl and rack construction is to compel the operating rod to be moved to the complete limit of its stroke after it has once been started in either direction, and thus to prevent the machine from being tam- 95 pered with in the attempt to work more than one pencil from the machine for each coin deposited.

The plate 23 has two upwardly extending ears 29, and pivoted thereto is a lock 30, 100 shown in detail in Fig. 6. The lock 30 is in the form of a flat channel plate and has two flanges 31 adapted to receive a coin, as indicated in Fig. 2, and a pin 32 is arranged in one flange 31 and acts as a gage to caliper 105 the coins and is so arranged that a coin or slug of less than the required width will slip directly through the lock, while a coin of the required width will be arrested by the gage 32. The lock has two ears 33 for its pivot 110

to bring the pivotal line at one side of the lock, and a weight 34 is secured to one ear and acts as a counterbalance to hold the lock normally in a vertical position, and the pivotal line of the lock is but slightly above the end of the operating rod 21, so that when the lock is upright, there being no coin in the machine, and it is attempted to push in the operating rod 21, the end of the latter will 5 strike against the flat back portion of the lock 30, immediately below the pivot thereof, as indicated in Figs. 1 and 4, and the lock being counterbalanced by the weight 34, will prevent further inward movement of the operating rod 21.

36 is a coin chute for conducting a coin from a coin slot 37 to the lock 30, and when a coin is inserted through the slot 37 it falls through the coin chute 36 and lodges in the lock 30, if it is the proper size, and the weight of the coin overcoming the weight 34 tilts the lock 30 into the position shown in dotted lines in Fig. 4, whereupon the operating rod 21 is free to be pushed in. The flat channel of lock 30 extends normally in a vertical plane, so as to receive the coin from the coin chute, and the pivotal axis of the lock is horizontal and is parallel to the plane of the said channel, so that in the tilting of the lock 30, under the weight of the coin, the plane of said channel will change from a vertical to a horizontal position, bringing the coin into longitudinal position directly in the path of the operating bar.

35 A button 38 is attached to the end of the shoe 22 and projects through the front wall 4. Upon the tilting of the lock 30 into the position shown in Figs. 1 and 4, upon pushing the button 38 inward the operating rod 40 21 slides over the horizontal face of the lock 30 and pushes the coin out therefrom and at the same time the inward movement of the operating rod 21 turns the lever 18 and retracts the ejector 13 into the position shown 45 in Fig. 3, thus removing the lugs 14 from under the lowermost pencil and allowing the latter to drop upon the shelf 6 close to the space 7. Two flat springs 39, see Figs. 1, 2 and 3, are secured to the respective vertical 50 ways 8 and lie close to the rear edge of the shelf 6 and prevent the pencil, which now rests upon the shelf 6, from being shaken through the slot prematurely. Upon removing the thumb from the button 38 the flat spring 17 reacts and forces back the ejector 13 and the lugs 14 pressing against the pencil 9 force back the pencil, overcoming the flat spring 39, and bring the pencil over the space 7, whereupon the pencil drops 55 through the space and rolls down the inclined ways 10 into the shallow groove 12, and is thus delivered to the customer, the parts at this time taking again the position shown in Fig. 2 except that the lock 30 is in 60 a vertical position, which position it assumes

immediately upon the ejection of the coin therefrom by the inward movement of the operating rod 21 before described. The coin upon being ejected from the lock 30 falls into a receptacle 40, the rear wall of 70 which has a flaring portion 41 to guide the coin into it. The receptacle 40 also has an inclined trough 42 the upper end of which, as shown in Fig. 4, lies directly under a hole 43 in the shelf 6, the hole 43 being directly 75 under the lock 30. The lower end of the trough 42 communicates with a slot 44 and if a coin or slug of less than the required width is inserted it will pass directly through the lock 30, as before described, thence fall 80 through the hole 43 and into the trough 42 and be returned through slot 44 to the customer.

The front wall 4 has a panel 45 which may be transparent or it may be covered with advertisement. The lower edge of the front wall 4 has two dowel pins 46 which detachably engage in the holes formed in the bottom 1, and a lock 47 is provided at the upper end of the front wall 4 to secure it to the top 90 5. By unlocking the lock 47 the front wall 4 may be tilted outwardly and then lifted up to disengage its dowel pins 46 and thus render the entire interior of the machine accessible for inspection, replenishment or repair. 95

What I claim is:—

1. In a coin controlled apparatus, a slideable operating bar, means for preventing reverse movement of the operating bar except from either limit of its stroke, a tilting lock 100 normally standing across the end of the operating bar, said tilting lock provided with means for receiving a coin and being counter-balanced to yield under the weight of the coin and said lock being so mounted that in 105 tilting under the weight of a coin it moves into position to bring the coin into the path of movement of the operating bar to enable ejection of the coin by the operating bar.

2. In a coin controlled apparatus, a slideable operating bar, means for preventing reverse movement of the operating bar except from the limit of its stroke, and a pivoted lock having coin holding means on one side of its pivot and a weight on the other side of 115 its pivot, the lock being in the form of a flat channel plate at the back of the end of the operating bar and its pivot being somewhat above the path of the operating bar and said lock being movable under the weight of a 120 coin to bring the coin into the path of the operating bar.

3. In a coin controlled apparatus, a slideable operating bar, a shoe on the operating bar, said shoe having a series of notches and 125 a deeper notch at each end of the series, a pawl swinging in either direction and adapted to occupy a central position in either of said notches, means for resiliently holding said pawl in its central position, a pivoted lock 130

having coin holding means on one side of its pivot, a weight on the lock on the other side of the pivot, the lock being arranged back of the end of the operating bar and being movable under the weight of the coin to bring the coin into the path of the operating bar.

4. In a coin controlled apparatus, a case having a removable front, coin slot mechanism in the case, a coin receptacle removably supported in the case below the coin slot mechanism and adapted to receive the coin therefrom, said receptacle having a trough also extending beneath the coin slot mechanism, said coin slot mechanism comprising a member movable to two different positions and adapted in normal position to receive and pass a defective coin into said trough, and adapted to receive and hold a proper coin and to turn under the weight thereof to such other position, and means for ejecting coin from the said member when in such other position to discharge the coin into the receptacle, the front of the case having an opening communicating with the lower end of said trough to discharge the coin therefrom.

5. In a coin controlled apparatus, a slide-able operating bar, means for preventing reverse movement of the operating bar except from either limit of its stroke, a vertical coin chute, a tilting lock normally standing across the end of the operating bar and extending vertically to receive the coin from the verti-

cal coin chute, said tilting lock provided with means for receiving the coin and being counterbalanced to yield under the weight of the coin, and said lock being pivotally mounted on a horizontal axis parallel to the plane of the coin as received therein from the coin chute so that in tilting under the weight of the coin it moves into position to bring the coin into a horizontal plane and into the path of movement of the operating bar to enable ejection of the coin by the operating bar.

6. In a coin controlled apparatus, a horizontally slidable operating bar, means for preventing reverse movement of the operating bar except from either limit of its stroke, a vertical coin chute, and a tilting lock having coin holding means on one side of its pivot formed as a flat channel, and having a weight on the other side of its pivot, and said lock being pivoted on a horizontal axis parallel to the plane of said flat channel so that in tilting under the weight of a coin the lock will move to bring the flat coin receiving channel from a vertical to a horizontal plane and to bring said coin into the path of the operating bar to enable ejection of the coin by the operating bar.

In testimony whereof, I have hereunto set my hand at Los Angeles, California, this 18th day of July, 1908.

AUGUST WAGNIERE.
